PERMANENT WAVE PROTECTOR

Agaton J. Parker, Chicago, Ill.

Application October 14, 1937, Serial No. 168,986

12 Claims. (Cl. 132—33)

The invention relates to a permanent wave protector and has as a general object to provide a new and improved device of that character.

A more particular object of the invention is to provide a permanent wave protector having a new and improved shield for the reception of a chemical pad employed in the baking of a wave.

Another object is to provide a permanent wave protector having a shield for the reception of a chemical pad employed in the baking of a wave which is releasably attached to the clamp of the protector so as to be out of the way during the winding of the hair on the winding rod.

Other objects and advantages will become apparent from the following detailed description taken in connection with the accompanying drawing, in which:

Fig. 1 is a top plan view of a protector embodying the features of the invention.

Fig. 2 is an enlarged end view of the protector taken from the right in Fig. 1.

Fig. 3 is an enlarged longitudinal sectional view taken approximately along the line 3—3 of Fig. 1.

Fig. 4 is an enlarged end view taken from the left in Fig. 1.

Fig. 5 is an enlarged transverse sectional view taken approximately along the line 5—5 of Fig. 1.

Fig. 6 is a plan view partially in section of the clamp of the protector.

Fig. 7 is an enlarged plan view of a shield forming a part of the protector.

Fig. 8 is an enlarged elevational view of the winding rod.

While the invention is susceptible of various modifications and alternative constructions, it is shown in the drawing and will be described hereinafter in a preferred embodiment, but it is not intended that the invention is to be limited thereby, but it is intended to cover all modifications and alternative constructions falling within the spirit and scope of the invention as defined by the appended claims.

As illustrated in the drawing, for purposes of disclosure, the permanent wave protector comprises, generally, a protective clamp 10 (see Fig. 6) which is adapted to be secured to a hank of hair to be waved adjacent the scalp, a winding rod 11 upon which the hair is wound, and means generally designated 12 for holding the winding rod against rotation after the hair has been tightly wound thereon. The clamp comprises two arms or jaws 13 and 14 which are pivotally secured together at one end and are adapted to be latched together at the other end, and when

latched assume a parallel relationship. Each arm has a metallic core consisting of sheet metal strips 15 and 16, respectively, bent to have a general U-shape in transverse cross section. Surrounding each core is a split, molded rubber casing 17 which has secured to the bottom side thereof a felt pad 18 in order further and effectively to prevent the transmission of heat from the protector to the scalp and head of the person whose hair is being waved. In addition to serving as insulators, the rubber casing 17 and the felt pads 18 constitute the means for gripping the hair and, therefore, are made sufficiently large so that they are firmly pressed together in gripping relationship when the clamp is in latched position.

As stated, the arms 13 and 14 are pivotally secured together at one end and herein this is accomplished by the insertion between the legs of the U-shaped strips 15 and 16 of a cross plate 20 and securing the same by rivets 21. Outwardly of the ends of the strips 15 and 16, the plate 20 is bent upwardly at right angles to form an upstanding ear 22. Preferably the end of one strip, herein the strip 15, is squared so that it forms a rigid connection with the plate 20, while the end of the other strip, herein the strip 16, is rounded (see Fig. 6) so that that strip may pivot with respect to the plate 20 and the arm 13.

The means for latching the free ends of the arms 13 and 14 in clamping relationship comprises a lever 25 pivotally mounted at 26 between a strip 27 and the parallel portion of a plate 28 which, like the plate 20, has a portion bent at right angles thereto to constitute an upstanding ear 29. The plate 28 and the strip 27 are pivotally secured as by a rivet 30 on the top and the bottom side of the strip 16. The corresponding end of the strip 15 has secured thereto a nose 31 (see Fig. 6) with which cooperates a cam 32 carried by the lever 25 for urging the arms 13 and 14 toward clamping engagement, and securing the arms in latched position. Each of the upstanding ears is formed with an outwardly opening slot 34 for the reception of the winding rod 11, as will presently be described.

As best seen in Figs. 1 and 8, the winding rod 11 includes a clip 36 which is pivotally mounted at one end of the rod and which overlies the center of the rod to secure a hank of hair thereto. Preferably the rod has a successively decreasing diameter from its ends toward the middle and at the middle is knurled to aid the clip 36 in securing the hair. At each end the rod has a reduced portion 37 adapted to be received

in the slots 34 as the hair is wound upon the rod 11.

At one end the rod 11 has fixed thereon a key 39 by means of which the rod may be revolved, 5 after it is in the slots 34, to effect a final tight winding of the hair about the rod. At the other end, the rod 11 is formed with teeth 40 to constitute part of a pawl and ratchet device serving to hold the rod 11 against rotation. Cooperating 10 with the teeth 40 is a pawl 41 pivotally mounted at 42 on the upstanding portion 29 of the plate 28. An arm 43 of the pawl extends beneath a leaf spring 44 secured by a rivet 45 to the plate 28 and is urged thereby toward engagement with 15 the teeth 40 of the rod 11.

It has been the practice in the past to bake the wave into the hank of hair wound upon the rod 11 by the application of heat generated electrically, but more recently it has become the practice to bake the hank of hair by the application 20 of a chemical heat generating pad. Means is provided herein for aiding in the application of such a chemical heat generating pad to the hank of hair wound on the rod 11. However, in order 25 that the clamp and the rod may be used for electric as well as chemical baking, this means is removably attached to the clamp. As disclosed herein the means takes the form of an elongated channel-shaped shield 47 which is adapted to be 30 mounted directly on the clamp 10 between the upper surface thereof and the winding rod 11. Extending longitudinally of the shield, centrally thereof, is a slot 48 opening through one end of the shield to permit the shield to be passed over 35 a hank of hair secured in the clamp by movement of the shield transversely of the hank of hair. In order that the shield may be readily removable from the clamp for various reasons, and yet may be easily and quickly mounted on the 40 clamp and secured thereon so that it will not be in the way during the winding of the hank of hair on the rod 11, it preferably has a mechanical interlocking engagement with the clamp at one 45 end and a simple frictional engagement at the other end. To that end, the end of the shield through which the slot 48 opens is formed with a notch 49 and the upstanding ear 29 is undercut at 50 and 51 so that it may be received within the notch 49 and also form shoulders retaining 55 that end of the shield 47 against outward movement. Similarly, the other end of the shield is formed with a notch 52 wide enough to receive the upstanding ear 22. This ear, however, is not undercut but there is riveted to the shield 47 a leaf spring 53 which frictionally engages the 60 ear 22 when the shield is mounted on the clamp yieldably to retain the shield against dropping off of its own accord. Preferably the end of the shield 47 having the notch 52 is strengthened and 65 reinforced by a transverse bead 54 and by bending inwardly the portion 55 of the shield severed to form the notch 52.

It is believed apparent from the foregoing that I have perfected a new and improved permanent 66 wave protector, and more particularly that I have perfected a protector readily capable of use for either electrical or chemical baking of the hank of hair. Moreover, I have perfected a protector capable of such dual use in which the shield 70 thereof, though removably attached to the protector proper, nevertheless is so mounted that it does not interfere with the winding of the hank of hair onto the winding rod.

I claim as my invention:

75 1. A permanent wave protector comprising, in

combination, a protecting clamp adapted to secure a hank of hair adjacent the scalp, a winding rod upon which the hank of hair is to be wound, a shield for the reception of a chemical heat pad employed for baking the wave having a portion disposed between said clamp and said rod, and cooperating engaging means on said clamp and said shield releasably and removably securing said shield on said clamp. 5

2. A permanent wave protector comprising, in combination, a protecting clamp adapted to secure a hank of hair adjacent the scalp, a winding rod upon which the hank of hair is to be wound, and a channel-shaped shield for the reception of a chemical heat pad for the baking of the wave having a portion disposed between said clamp and said rod, and means on said shield frictionally engaging a portion of the clamp to be removably supported thereby during the winding of the hair onto the winding rod. 10 15

3. A permanent wave protector comprising, in combination, a protective clamp adapted to be secured to a hank of hair adjacent the scalp having an upstanding ear at each end thereof, a winding rod upon which the hair is wound adapted to be supported in the ears in final position, and a shield for the reception of a chemical heat pad applied to the rod for the baking of the wave, said shield having an interlocking engagement with one ear and a frictional engagement with the other ear whereby it is removably supported on the clamp during the winding of the hair upon the rod. 20 25 30

4. A permanent wave protector comprising, in combination, a protective clamp adapted to be secured to a hank of hair adjacent the scalp having an upstanding ear at each end thereof, a winding rod upon which the hair is wound adapted to be supported in the ears in final position, and a shield adapted to be interposed between the clamp and the winding rod to aid in the application of a chemical heat pad to the rod, said shield comprising a channel-shaped member having a longitudinally extending slot opening through one end thereof for the application of the shield to the clamp by longitudinal movement of the shield transversely of the hank of hair secured in the clamp, a notch in the end of the shield through which the slot opens for an interlocked engagement with the upstanding ear at that end of the clamp, a notch at the other end of said shield for receiving the upstanding ear at that end of the clamp, and a spring for frictionally engaging the upstanding ear removably to secure that end of the shield to the clamp. 40 45 50 55

5. A permanent wave protector comprising a clamp adapted to be secured to a hank of hair to be waved adjacent the scalp composed of a pair of jaws pivotally secured together at one end and adapted to be secured in clamping relation by latch means at the other end, said jaws being covered with suitable insulating material to prevent the transmission of heat to the scalp of the person whose hair is being waved, a winding rod upon which the hair is to be wound, a shield adapted to be interposed between the clamp and the winding rod in its final position to aid in the application of a chemical heat generating pad employed in baking the wave, said shield being removably secured to said clamp, and pawl and ratchet means for holding said winding rod against rotation in its final position. 60 65 70 75

6. An element for use with a permanent wave 75

5 protector in the baking of a wave by the application of chemically generated heat comprising a channel-shaped member forming a shield having a longitudinally extending slot opening through one end thereof, and means for removably attaching said shield to the protector.

7. An element for use with a permanent wave protector employed in the permanent waving of hair by the application of heat chemically generated comprising an elongated channel-shaped member having a slot extending longitudinally thereof and opening through one end, a shallow notch at the end through which said slot opens, a shallow notch at the opposite end, and a leaf spring at that same end disposed to extend slightly beyond the edge of the notch.

8. An element for use with a permanent wave protector employed in the permanent waving of hair by the application of heat chemically generated comprising an elongated channel-shaped member having a slot extending longitudinally of the intermediate portion of the member and opening through one end, a shallow notch at the end of the intermediate portion through which said slot opens, a shallow notch at the opposite end, a leaf spring at that same end disposed to extend slightly beyond the edge of the notch frictionally to engage a part received in the notch, and a bead and an upstanding flange 25 extending transversely of said intermediate portion adjacent said last mentioned notch to reinforce the member.

9. A permanent wave protector comprising, in combination, a protecting clamp adapted to secure a hank of hair adjacent the scalp, a winding rod upon which the hank of hair is to be wound 30

and a shield for the reception of a chemical heat pad employed for baking the wave removably secured on said clamp and having a longitudinal slot opening through one end thereof for the application of said shield to said clamp intermediate said clamp and said rod by longitudinal movement of said shield transversely of the hank of hair secured in said clamp.

10. A permanent wave protector comprising, in combination, a protecting clamp adapted to secure a hank of hair adjacent the scalp, a winding rod upon which the hank of hair is to be wound, a shield for the reception of a chemical heat pad employed for baking the wave having a longitudinal slot opening through one end thereof for the application of said shield to said clamp intermediate said clamp and said rod by longitudinal movement of said shield transversely of the hank of hair secured in said clamp, and cooperating engaging means on said clamp and said shield 15 releasably and removably securing said shield on said clamp.

11. In a permanent wave protector having a clamp adapted to be secured to a hank of hair, a shield for the reception of a chemical heat generating pad, and engaging means on said shield adapted for cooperation with means on said clamp releasably and removably attaching said shield to the protector.

12. In a permanent wave protector, a shield 25 for the reception of a chemical heat generating pad having a longitudinal slot opening through one end thereof to permit application of the shield by longitudinal movement of the shield.
